CLAIM

The ornamental design for a device for the distribution of liquids or gases, as shown and described.

DESCRIPTION

FIG. 1 is a perspective view of a first embodiment for a new and ornamental design for a device for the distribution of liquids or gases;

FIG. 2 is a first side elevation view thereof;

FIG. 3 is a second side elevation view thereof;

FIG. 4 is a front elevation view thereof;

FIG. 5 is a top plan view thereof;

FIG. 6 is a bottom plan view thereof;

FIG. 7 is a perspective view of a second embodiment for a new and ornamental design for a device for the distribution of liquids or gases;

FIG. 8 is a first side elevation view thereof;

FIG. 9 is a second side elevation view thereof;

FIG. 10 is a front elevation view thereof;

FIG. 11 is a top plan view thereof; and,

FIG. 12 is a bottom plan view thereof.

The broken lines shown in the drawings illustrate environment only that form no part of the claim.

1 Claim, 10 Drawing Sheets
